UNITED STATES PATENT OFFICE

ADOLPH A. THOMAS, OF NEW YORK, N. Y.

ELECTRIC PHONOGRAPH

Application filed December 4, 1926. Serial No. 152,525.

My invention relates to electric phonographs, and its object is to provide an improved instrument of that type embodying various features of novelty, as will later be explained in detail. The main purpose of my invention is to produce an electric phonograph of the portable or table type, in which all the parts are mounted in a carrying case of comparatively small dimensions, and yet which is capable of giving a reproduction of great volume equal to that of large cabinet phonographs. I do not want to create the impression, however, that this invention is limited to portable phonographs, for it may 10 obviously be installed in stationary household cabinets; I merely want to emphasize the point that my invention contains novel features particularly applicable to portable electric phonographs.

One of the important features of my invention is a loudspeaking diaphragm of suitable construction mounted inside the lid of the carrying case without interfering with the closing of the lid. The electromagnetic driving unit for the diaphragm is also mounted on the lid. The diaphragm and its driving unit are preferably carried by a frame which is secured as a unitary attachment to the inside of the lid. If the carrying case is made 20 rectangular, the diaphragm may be elliptical or oval, so as to have maximum vibrating surface within the rectangular area of the lid. There is ample room in the case to house the various electrical devices that go to make up 30 the electric transmission system between the reproducer and the driving unit. In a preferred embodiment of my invention as applied to portable phonographs, there is a compartment for records below the motor chamber. The cover of this record compartment is automatically locked and unlocked by merely closing and opening the lid.

A further feature in my new electric phonograph comprises means for automatically 40 controlling the reproducer circuit by the

movements or position of the lid. When the lid is closed, it operates a switch inside the case to open all battery circuits, so that no current can flow when the case is closed and carried about. When the machine is to be 50 used and the lid thrown open, the switch is automatically closed and the reproducing circuits are in operative condition. In a preferred form of my invention, the lid-controlled locking means for the record compartment also controls the battery switch.

The foregoing and other features and advantages of my invention will be fully understood from a detailed description of the accompanying drawings, in which I have 60 illustrated two constructions of portable electric phonographs as exemplifications of my invention. In these drawings—

Fig. 1 represents a plan view of a phonograph constructed in accordance with my invention, the lid being shown open;

Fig. 2 is a front view of the construction shown in Fig. 1, a portion of the carrying case being broken away to show certain parts inside;

Fig. 3 is a cross-section on line 3—3 of Fig. 1;

Fig. 4 is a fragmentary detailed view showing how the driving unit is supported in the frame that carries the diaphragm;

Figs. 5 and 6 show two forms of electric transmission systems between the electric reproducer and the loudspeaker diaphragm;

Fig. 7 is a plan view of a slightly modified construction;

Fig. 8 shows a front view of Fig. 7.

Referring to the construction illustrated in Figs. 1—4, there is a suitable carrying case or cabinet indicated as a whole by C, which is so proportioned and designed as to house 85 compactly all the parts that go to make up a complete electric phonograph. A lid 10 is hinged at 11 to the rear edge of the case, which may be made of wood, fiber, sheet metal, or any other appropriate material. A collaps- 90

ible link connection 12, or other practical means, holds the lid in upright open position. When the lid 10 is closed, the case or cabinet C is a practically dust-proof box, which can be carried about like a small piece of hand-baggage. For this purpose the case is provided with a handle 13, and the lid 10 is locked in closed position by any practical means, not necessary to show or describe.

10 On the inside of lid 10 is secured a loud-speaking diaphragm 14, which is preferably (but not necessarily) in the shape of a cone with a circular or elliptical base. Cone diaphragms, as they are usually called in the trade, are well known and are usually made of stiff paper or parchment, but they may also be made of light sheet metal, celluloid, stiffened impervious cloth, and other practical materials. The diaphragm may also be 20 made flat, as of thin corrugated paper or metal. By making the diaphragm 14 of elliptical shape, it is possible to support a diaphragm of maximum acoustic surface within the rectangular area of lid 10, as plainly 25 shown in Fig. 2. In the broader aspect of my invention, any practical form and shape of loudspeaking diaphragm may be secured to the inside of lid 10. Instead of mounting the diaphragm directly on the inside wall of 30 the lid, I prefer to use a supporting frame 15 having an elliptical ring 16 to which the edge of the diaphragm is secured, as by means of a clamping ring 17 and screws or rivets 18. The diaphragm 14 is held spaced from the 35 inner face of the lid by lugs 19 on frame 15. Screws or other fastening members 20 pass through lugs 19 into the lid for rigidly securing the frame and all parts carried thereby to the inside of the lid. As seen in Fig. 3, the 40 lugs 19 hold the supporting ring 16 spaced from the lid so that sound waves produced back of the diaphragm will readily find their way into the free air. If desired, lid 10 may be so constructed as to act in the manner of a 45 sounding board for augmenting the vibrations of diaphragm 14. It should be noted that the lid also serves to direct the sound waves forwardly toward the listener, thereby increasing the acoustic effect of the dia- 50 phragm. Instead of being flat, as shown, the lid may be domed outwardly, or it may slightly bulge inwardly at the center. The lid 10 is preferably provided with a peripheral flange or extension adapted to form a shal- 55 low sound chamber in which the cone dia- phragm is mounted and which acts to amplify the reproduction, particularly if the lid is constructed like a sounding board. As seen in Figs. 1 and 7, the sound waves produced by 60 the rearward movements of the diaphragm strike the lid and are prevented from scattering in all directions by the peripheral flange or lid. In other words, the sound chamber or recess formed by the lid directs the waves 65 forward to mingle with and reinforce other

sound waves of the diaphragm, whereby the final volume is increased and the tone quality of the reproduction improved.

The frame 15 is provided with cross-arms 21, which unite at the center to form a cylindrical housing 22 for supporting an electro-magnetic driving unit 23. Since driving units of this kind are well known in the art, I need not show or describe any structural details thereof. It is enough to say that the vibratory armature of driving unit 23 is connected to the center of diaphragm 14 by a link 24, which is to be considered as diagrammatically representing any operative connection (whether mechanical or electromagnetic) between the diaphragm and the driving mechanism. The unit 23 is rigidly secured in support 22 in any practical way. In Figs. 3 and 4, I have shown a spring bar 25 pivoted on a central stud 26 projecting from the casing of unit 23. The support 22 is provided at one end with an inturned annular flange 27, and at the other end with an annular groove 28 formed by an overlying shoulder 29, which is slotted at 30 to permit entry of the spring bar 25 into locking groove 28. When the spring bar is turned under shoulder 29, the casing of unit 23 is rigidly held against the inturned flange 27 and thus securely locked in position. This locking arrangement permits ready removal of the unit when desired by simply turning the bar 25 into line with slots 30. The casing of unit 23 is provided with a pair of binding posts 31 for receiving conductors 32, which form part 100 of an electric transmission system between the electric phonograph reproducer and the driving unit, as will later be explained in detail. The diaphragm 14 and driving unit 23 are mounted on frame 15 and adjusted for 105 the best possible operation before the frame is secured to the lid.

The carrying case or cabinet C is provided with a motorboard 33 on which is mounted a turntable 34 driven by a motor 35, which may be electrical or mechanical and of any practical construction. As phonograph motors, both electrical and mechanical, are well known in the art and are sold separately by manufacturers, I need not show or describe 110 any details of the driving motor 35. If a mechanical motor is used, a winding crank is inserted through a hole 36 in the front wall of the case. On the motorboard 33 is mounted a vertically and horizontally movable arm 120 37 carrying at its outer end an electric phonograph reproducer 38 adapted to receive a suitable stylus for playing phonograph records. There are several types and makes of 125 electric phonograph reproducers on the market, and so I need not show or describe the structural details of reproducer 38. It will be sufficient to refer to the diagrams of Figs. 5 and 6, where 38^a represents a reproducer of the microphone type, and 38^b indicates a re- 130

producer of the electromagnetic type, usually called a pick-up. Briefly stated, reproducer 38^a of Fig. 5 comprises a disk 39 connected to the stylus arm and adapted to press against carbon granules 40 to vary the resistance between the disk and a fixed terminal plate 41. In the electric reproducer or pick-up 38^b of Fig. 6, there is a vibratory magnetic diaphragm or armature 42 in operative relation to the pole pieces of a permanent magnet 43 provided with one or more coils 44, which are properly connected in circuit, as will later be explained. It will be understood from the preceding remarks that, when I refer to the part 38 as an electric reproducer, I mean any practical device capable of producing electric impulses in accordance with the vibrations of a record-playing stylus, whether on lateral-cut records or vertical-cut records. If 20 the reproducer arm 37 is in the form of a tube, the connecting leads of the reproducer may be concealed therein. To hold the reproducer arm 37 in rest position, I provide a suitable support 45 which holds the arm 25 in fixed position when the machine is carried about. A simple construction of support 45 would be a pair of spring fingers adapted to grip the arm and hold it firmly clamped until released. This will be understood without 30 additional illustration.

Below the motorboard 33 are two vertical partitions 46 which form a pair of lateral chambers 47 and 48. In these two chambers are housed the various electrical parts, such 35 as batteries, amplifying tubes, transformers, resistances, etc., that go to make up a suitable amplifying transmission system between the reproducer 38 and driving unit 23. The precise disposition of these electrical parts 40 in chambers 47 and 48 may be varied to obtain the most compact and convenient arrangement in any given instance. Merely by way of example I have roughly indicated in chamber 47 a pair of audio-frequency 45 transformers 49 and 50 and a pair of amplifying vacuum tubes 51 and 52. In chamber 48 I have indicated batteries 53 and 54, which may be considered, respectively, the filament and plate batteries of the amplifying system. It goes without saying that these various electrical devices are properly supported in chambers 47 and 48, so that they 50 will not be dislodged or disturbed during transportation of the machine. I have not 55 deemed it necessary to show any details of such supporting means, for these are well within the skill of the mechanic. The chambers 47 and 48 are provided with covers 55 hinged at 56, so as to open sideways. Each 60 cover has a finger-piece 57 for easy manipulation, and the cover for chamber 47 also has ventilating holes 58. Suitable means are provided for holding the covers 55 against accidental opening when the machine is carried about. When the covers 55 are closed, 65

they form part of the top board of the case, being in effect continuations of motorboard 33.

Referring to Fig. 2, it will be seen that the motor chamber is closed at the bottom by a horizontal partition 59, which extends between the upright partitions 46 and may conveniently be secured thereto. Between the horizontal partition 59 and the bottom of the cabinet is formed a compartment 60 adapted to receive a stack of phonograph records. Instead of putting the records directly in compartment 60, I prefer to provide a tray 61 adapted to slide in and out of the compartment. The front of tray 61 is 70 closed by a panel 62, which normally forms part of the outer cabinet wall. A knob 63 permits the tray to be easily pulled out for access to the records. To the sides of the record tray 61 are secured two angle pieces 75 64 having each a hole 65 in alignment with a hole 66 in the horizontal partition 59. In line with each pair of holes 65 and 66 is mounted a slidable latch-bar or locking bolt 67 arranged to project through an opening 80 68 in motorboard 33. The openings 66 and 68 act as supporting bearings for the latch-bar, as may be seen from Fig. 2. A coil spring 69 surrounds each latch-bar for normally forcing the same upwardly. A suitable stop 70 carried by the latch-bar limits the upward movement thereof under the action of spring 69. It is clear from Fig. 2 that, when the latch-bars 67 are pushed down 85 against the springs, the lower ends thereof 90 pass through the holes 65 in the angle pieces 64 of record tray 61, as indicated by dotted lines 67'. This locks the record tray in closed position. I have provided means for automatically sliding the bars or bolts 67 into locking position when the lid 10 is closed. In the present instance, the lid is provided 95 on the inside with a pair of studs 71 arranged to engage the heads of locking bars 67 and force the same inwardly when the lid is 100 closed. In this way, the mere closing of lid 10 automatically locks the record tray 61 without any attention on the part of the user. When the lid is thrown open, the springs 69 105 push the bars 67 outwardly into releasing 110 position. Although I have shown a pair of locking bars, one would be sufficient. 115

In order to prevent waste of battery current when the machine is not in condition for use, I provide a switch adapted to be automatically opened when the lid 10 is closed. For convenience, I use one of the locking bars 67 for operating the switch. Referring to Fig. 2, there is a switch consisting of a pair of contacts 72 mounted in fixed position in chamber 120 48, as by being secured to the inside wall of the front panel of the cabinet. The switch contacts 72 are insulated and properly connected in circuit, as will presently be explained in connection with the wiring dia- 125 130

grams of Figs. 5 and 6. The adjacent locking bar 67 carries a lateral conducting arm 73 arranged to extend into chamber 48 through a slot 74 in partition 46. When the lid 10 is opened and the bar 67 forced upwardly by spring 69, the conducting arm 73 connects the spring contacts 72 and the battery circuit is closed. When the lid 10 is closed and the locking bar 67 depressed into locking position, as already explained, the connecting arm 73 breaks contact with the switch 72 and moves into the position indicated by dotted lines 73' in Fig. 2, whereby all battery circuits are opened. The contacts 72 are preferably of spring metal so as to make good contact with arm 73. Any other practical construction of switch may be employed.

As heretofore stated, the electric reproducer 38 may represent a device of the microphone type, as indicated by reproducer 38^a in Fig. 5, or it may represent a reproducer of the electromagnetic type, as indicated by reproducer 38^b in Fig. 6. With a microphone reproducer, the transmission system for operating the loudspeaking diaphragm 14 is usually simpler than where an electromagnetic reproducer is used. Two illustrative amplifying systems between the reproducer and the diaphragm are indicated in Figs. 5 and 6, which will now be described.

In Fig. 5 the contacts 39, 40 and 41 of the microphone reproducer are connected in the circuit of a battery 75 of suitable voltage. A radio filament battery will usually answer the purpose. The switch contacts 72, previously mentioned, are included in the battery circuit. The connecting arm 73 is shown in full lines to close the switch, and in dotted position to indicate the opening of the switch. A rheostat 76 is preferably included in the battery circuit to regulate the volume of reproduction. The electric impulses produced by the vibratory movements of the stylus arm are amplified by means of a step-up transformer 77, the primary of which is connected in battery circuit and the secondary in the circuit of the electromagnetic driving unit 23. If desired, a further amplification of the current impulses produced in the battery circuit may be obtained by using additional transformers, or employing amplifying tubes. Ordinarily, however, a single amplifying transformer will be found sufficient in the case of a microphone reproducer.

In Fig. 6 we have a somewhat more elaborate transmission system, utilizing a pair of amplifying tubes 51 and 52 and a pair of coupling transformers 49 and 50. The tubes 51 and 52 are of usual construction, including a filament 78, a grid 79, and a plate 80. The three electrodes of tube 52 are marked 78', 79' and 80', so as to distinguish them from the corresponding electrodes of tube 51. A wire or other conductor 81 connects grid 79 with

one end of coil or coils 44, the other end of which is connected through a wire 82 with one side of filament 78. The two filaments 78 and 78' are connected in parallel with a battery 53 by means of conductors 83, 84, 85 and 86. In the common connection 87 is included the switch 72 and a rheostat 88. What has previously been said about the controlling action of switch 72-73, is fully applicable to the circuit of filament battery 53. The plate electrode 80 of tube 51 is connected to one end of the primary coil 89 of transformer 49, and the other end of that coil is connected by a conductor 90 to the positive terminal of the plate battery 54. A controlling rheostat 91 is preferably included in the last mentioned connection. The negative terminal of battery 54 is connected by wire 92 to the common lead 83-85 of the filament circuit. The grid electrode 79' of tube 52 is connected by wire 93 to one terminal of the secondary coil 94 of transformer 49. The other terminal of secondary coil 94 is connected to one side of filament 78' by wire 95. The plate electrode 90' of tube 52 is connected by wire 96 to one end of the primary coil 97 of transformer 50. The other end of primary coil 97 is connected through conductor 98 with the positive pole of battery 54. The secondary coil 99 of transformer 50 is connected to the electromagnetic driving unit 23.

The operation of the amplifying transmission system of Fig. 6 will be clear to those skilled in the art, but I may summarize it in a few sentences. As the magnetic diaphragm or armature 42 vibrates under the action of the stylus movements, current impulses are induced in coil or coils 44, the circuit of which is closed across the electronic path between the grid and filament of tube 51. The potential variations thus set up in grid 79 cause amplified current impulses in the circuit of primary coil 89, and these current impulses induce corresponding voltage variations in the grid circuit of tube 52. This gives us a second stage of amplification, so that the transformer 50 finally transmits greatly amplified current impulses to the driving unit 23. The filament rheostat 88 and plate rheostat 91 are adjusted to give the best acoustic results in each particular case.

The audio-frequency amplifying system of Fig. 6 is in operative condition only when the circuit of filament battery 53 is closed by the switch arm 73. If this transmission system is provided, as I prefer, with the automatic switch control described in connection with Fig. 2, then the filament circuits of amplifying tubes 51 and 52 are closed only when the lid 10 is open and are automatically broken when the lid is closed. No switch for the plate battery 54 is required, because the plate circuits are not closed unless the filaments are heated to provide an electronic conducting

path from plate to filament. Consequently, when the filament circuit or circuits are broken, the plate battery circuit is automatically interrupted.

5 I wish to make it clear that the amplifying systems of Figs. 5 and 6 are not to be considered as limitations of my invention, but merely as illustrative of any practical means for electrically transmitting the action of the electric reproducer to the loudspeaking diaphragm so as to obtain a reproduction of good quality and desired volume. From the radio art may be borrowed several types of audio-frequency amplifying systems. For example, 10 15 a three-stage resistance-coupled or impedance-coupled amplifier, with a power tube in the last stage, will be found to give excellent results. Of course, if the phonograph is to be carried about, as on trips, the amplifying system should be as simple as possible, so as to reduce the total weight of the instrument.

In the modification of Figs. 7 and 8, the longer sides of lid 10 extend upwardly when the lid is opened, and the diaphragm 14 is therefore arranged with its major axis vertical. The electrical devices in this instance are housed in a chamber 100 arranged back of the turntable and closed by a hinged cover 101. The chamber 100 may have a transverse 25 30 partition 102 to provide a shallow space 103 adapted to house the crank for winding the spring motor of the machine. If an electric motor is used, the space 103 may be dispensed with or otherwise utilized. The dotted outlines appearing in chamber 100 of Fig. 7 indicate that the battery 75 and transformer 77 are suitably mounted within the chamber. Except for the differences noted, the construction of Figs. 7 and 8 is identical with that 35 40 45 of Figs. 1 and 2, so that the detailed description of the last-mentioned figures should be regarded as applicable to Figs. 7 and 8 without the need of repetition. For convenience, I have numbered corresponding parts of these two constructions with the same reference characters. Although the carrying case in Figs. 7 and 8 is shown as being practically of the same size as that of Figs. 1 and 2, a construction like that of Figs. 7 and 8 may be 50 55 60 embodied in a case or cabinet considerably smaller than that required for the construction of Figs. 1 and 2.

The amplifying connections between the stylus arm of electric reproducer 38 and the driving unit 23 of diaphragm 14 are such 55 60 65 that the volume of reproduction can be made equal to, and indeed greater than, the volume obtainable from large cabinet phonographs containing amplifying horns. By mounting the loudspeaking diaphragm 14 on the inside 70 75 80 of the lid, the diaphragm is in the best position for reproduction, because the lid is upright when the machine is used and therefore the sound is thrown forwardly. The lid 10 acts not only as a sound-directing wall,

but also as a sounding board to amplify or augment the waves produced by the diaphragm. It is thus possible, under my invention, to construct an electric phonograph of such compactness and small weight that it may easily be carried about and stored in a small space, and yet capable of giving a reproduction comparable in volume and quality with that of high-priced cabinet phonographs.

It need hardly be mentioned that the construction and mounting of diaphragm 14 are such as to permit closing of the lid when the reproducer arm 37 is supported in idle or rest position, as shown in dotted lines in Fig. 1 and in full lines in Fig. 7. The electrical parts of the transmission system are easily accessible by simply lifting the covers 55 and 101, so that batteries may be replaced without trouble. The record compartment 60 enables the user to provide himself with the desired music when he takes the phonograph with him on a trip. My new portable phonograph is especially useful in city apartments where rooms are small and space 90 95 scarce. The phonograph may be placed on a table or chair for playing, and when not in use it may be hidden away in a closet or other place where it will not be in the way.

Although I have described certain specific 95 constructions and circuit arrangements, I want it understood that I have done so merely by way of example and not as a limitation of my invention. Various changes and modifications will doubtless occur to those skilled 100 105 in the art, without departing from the scope of the invention as defined in the following claims.

I claim as my invention:

1. An electric phonograph comprising a 105 substantially flat carrying case of rectangular shape, said case having a pivoted lid and a top board provided with a turntable, the shallow space between said topboard and the bottom of the case comprising at least two 110 chambers arranged side by side, one of said chambers containing driving mechanism for the turntable and the other chamber containing electric devices adapted to form a system for transmitting electric impulses, an 115 electric reproducer mounted on said topboard and operatively connected with said devices, a loudspeaking diaphragm secured to the inside of said lid and spaced therefrom, said diaphragm and reproducer being so arranged 120 as to permit closing of the lid, and an electromagnetic driving unit carried by said lid for vibrating said diaphragm, said unit being operatively connected with said devices.

2. An electric phonograph comprising a 125 case of substantially rectangular shape and having a hinged lid at the top, an elliptical diaphragm mounted on the inside of said lid and open on both sides to the outer air when the lid is open, an electromagnetic unit 130

also carried by said lid for operating said diaphragm, the major axis of said elliptical diaphragm being in the direction of the greater length of said lid, whereby a diaphragm of maximum perimeter and acoustic area is supported within the rectangular space of the lid, an electric reproducer operatively mounted on the top board of said case, said diaphragm and reproducer being so arranged as to permit closing of the lid, and electric mechanism for transmitting the vibrations of said reproducer to said driving unit.

3. A portable electric phonograph comprising a substantially flat carrying case having a pivoted lid and a topboard, there being a shallow space between said topboard and the bottom of the case, a casting having an annular rim and integral lugs projecting outwardly therefrom, fastening devices engaging said lugs to secure said frame rigidly to the inner wall of said lid, a loudspeaking diaphragm fastened to said rim, integral arms on said casting terminating in a head, an electromagnetic unit mounted in said head for operating said diaphragm, said lugs holding said rim and diaphragm spaced from the supporting wall, an electric reproducer mounted on said topboard, and electric mechanism in said shallow space for transmitting the vibrations of said reproducer to said driving unit.

4. An electric phonograph comprising a substantially rectangular case, a hinged lid forming the top of said case, a top-board fixed in the body of said case, a partition arranged below said topboard substantially parallel therewith to provide an upper chamber and a lower chamber, said upper chamber containing a motor for driving the turntable, a movable panel for said lower chamber which is adapted to receive records, said panel when closed forming part of the outer structure of said case, an electric reproducer operatively mounted on said topboard, a loudspeaking diaphragm mounted on the inside of said lid without interfering with the closing thereof, an electromagnetic unit also carried by said lid to operate said diaphragm, electric devices for transmitting the electric impulses of said reproducer to said driving unit, a locking member for said movable panel, and means on said lid for automatically actuating said member to lock said panel when the lid is closed, said member automatically unlocking the panel when the lid is raised.

5. In an electric phonograph, a cabinet having a lid hinged at the top, electric reproducing mechanism in said cabinet, said mechanism including an electric circuit, a switch for said circuit, said switch including a vertically movable member which normally tends to close the circuit, and a projection on said lid for depressing said member to

open said switch when the lid is closed, said member automatically closing said switch when the lid is raised.

6. In an electric phonograph, a case having a hinged lid and a compartment provided with a movable cover which normally forms part of the outer case structure, a movable locking member for said cover, means on said lid for moving said member into locking position when the lid is closed, said member automatically moving into unlocking position when the lid is opened, electric reproducing mechanism in said case, and a switch included in said mechanism and controlled by said member.

7. A portable electric phonograph comprising a substantially flat rectangular carrying case having a hinged lid at the top, a horizontal top board in the body of said case, a horizontal partition between said top board and the bottom of said case to provide an upper chamber for the motor and a lower shallow chamber adapted to receive records, said case having a third chamber arranged alongside said lower and upper chambers to house electric devices adapted to transmit electric impulses, an electric reproducer mounted on said top board, a loudspeaking diaphragm and its electromagnetic driving unit supported in said lid, and means for operatively connecting said reproducer and driving unit in circuit with said devices, said diaphragm and reproducer permitting closure of the lid.

8. An electric phonograph comprising a cabinet having a top board and a hinged lid at the top, means for holding said lid raised in open position, a loudspeaking diaphragm mounted on the inside of said lid, an electromagnetic unit also carried by said lid to operate said diaphragm, a vertical partition in said cabinet below the top board to form a compartment for the motor and another compartment for electrical devices adapted to operate as a transmission system for said unit, said compartments being arranged side by side, a cover for said second compartment arranged to form a continuation of said top board, and an electric reproducer operatively mounted on the top board and electrically connected with said system, said diaphragm and reproducer being so arranged as to permit closing of the lid.

9. An electric phonograph comprising a case of substantially flat rectangular shape, said case including a hinged lid at the top adapted to be held in raised open position, vertical partitions arranged in the body of said case to divide the same into a central compartment for the motor and two side compartments for electrical devices adapted to form a transmission system for electric impulses, a motor board covering the central compartment, a movable closure for each side compartment, said closures forming a con-

tinuation of said motor board, an electric reproducer operatively mounted on the motor board and electrically connected with said system, a loudspeaking diaphragm mounted 5 on the inside of said lid without interfering with the closing thereof, and an electromagnetic driving unit also carried by said lid for operating said diaphragm, said lid when raised holding the diaphragm in substantially upright position open to the free air.

10. An electric phonograph comprising a case of substantially rectangular shape, said case including a hinged lid at the top provided with means to hold it in raised open 15 position, vertical partitions arranged in the body of said case to divide the same into a central compartment and two side compartments, a horizontal partition in said central compartment to divide the same into an upper 20 chamber and a lower chamber, a movable panel for said lower chamber which is adapted to receive records, said panel when closed forming part of the outer structure of said case, a motor board fixed in the upper part of 25 said case to cover said upper chamber which contains a motor for driving the turntable, electric devices in said side compartments adapted to form a transmission system for electric impulses, a top cover for each side 30 compartment, said side covers forming in effect continuations of said motor board to completely close the body of said case at the top, an electric reproducer operatively mounted on the motor board and electrically 35 connected with said system, a loudspeaking diaphragm mounted on the inside of said top lid without interfering with the closing thereof, and an electromagnetic driving unit also carried by said lid for operating said 40 diaphragm, said lid when raised holding the diaphragm in substantially upright position open to the free air.

11. An electric phonograph comprising a case of substantially rectangular shape, said 45 case including a hinged lid at the top provided with means to hold it in raised open position, vertical partitions arranged in the body of said case to divide the same into a central compartment and two side compartments, a horizontal partition in said central 50 compartment to divide the same into an upper chamber and a lower chamber, a movable panel for said lower chamber which is adapted to receive records, said panel when closed 55 forming part of the outer structure of said case, a motor board fixed in the upper part of said case to cover said upper chamber which contains a motor for driving the turntable, electric devices in said side compartments 60 adapted to form a transmission system for electric impulses, a top cover for each side compartment, said side covers forming in effect continuations of said motor board to completely close the body of said case at the 65 top, an electric reproducer operatively

mounted on the motor board and electrically connected with said system, a loudspeaking diaphragm mounted on the inside of said top lid without interfering with the closing thereof, an electromagnetic driving unit also 70 carried by said lid for operating said diaphragm, said lid when raised holding the diaphragm in substantially upright position open to the free air, a locking device for said movable panel, means on said lid for automatically actuating said device to lock said panel when the lid is closed, and a switch in 75 said system automatically opened by said device when the latter is moved into locking position.

12. An electric phonograph comprising a cabinet having a pivoted lid and a topboard, said lid being provided with a peripheral flange which forms a shallow chamber, a casting having an annular rim and integral 80 lugs projecting outwardly therefrom, fastening devices engaging said lugs to secure said frame rigidly to the inner wall of said lid whereby said rim and lugs are mounted in said chamber, a loudspeaking diaphragm 85 fastened to said rim, integral arms on said casting terminating in a head, an electromagnetic unit mounted in said head for operating said diaphragm, said lugs holding said rim and diaphragm spaced from the supporting wall so that the open shallow chamber formed by the flanged lid acts to reflect sound forwardly and thereby amplifies the reproduction, an electric reproducer mounted on said topboard, and electric mechanism 90 for transmitting the vibrations of said reproducer to said driving unit.

13. An electric phonograph comprising a cabinet provided with elongated sound board having a peripheral extension to form a sound chamber, an elliptical diaphragm mounted on said board and spaced therefrom, the major axis of said diaphragm being in the direction of the greater length of said board so that a diaphragm of maximum perimeter 100 and acoustic area is supported in said chamber, and electric reproducer means for operating said diaphragm, said chamber amplifying the reproduction of the diaphragm.

14. In an electric phonograph, a cabinet 105 provided with electric reproducing mechanism, a switch in said cabinet for controlling a circuit of said mechanism, said switch including a spring-pressed movable member normally projecting out of the cabinet to 110 close said circuit, and a hinged closure on said cabinet adapted when closed to engage said member and move it inwardly into circuit-breaking position, said closure when opened moving out of engagement with said switch 115 member which is thereby released and automatically actuated into circuit-closing position.

15. In an electric phonograph, a cabinet 120 provided with electric reproducing mecha-

nism, a switch in said cabinet for controlling a circuit of said mechanism, said switch including a spring-pressed plunger normally projecting out of the cabinet to close said circuit, and a hinged closure on said cabinet 5 adapted when closed to push said plunger inwardly into circuit-breaking position, said closure when opened moving out of engagement with said plunger which is thereby released and thrown by the spring into normal 10 circuit-closing position.
